Primary Examiner — Barbara Fox*Assistant Examiner* — Dana K Weiland*(74) Attorney, Agent, or Firm* — NSIP Law(57) **CLAIM**

The ornamental design for a tablet computer, as shown and described.

DESCRIPTION

FIG. 1 is a perspective view of a tablet computer showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof, in which a stand part that rotates on a hinge is in a closed position;

FIG. 9 is a rear perspective view thereof, in which a stand part that rotates on a hinge is in an open position; and,

FIG. 10 is a rear perspective view thereof, in which a keyboard part that separates from the remaining tablet computer is in a detached state.

The broken lines represent portions of the tablet computer that form no part of the claimed design. The shade lines in the figures show contour and not surface ornamentation.
